UNITED STATES PATENT OFFICE

2,600,839

CONDIMENT HOLDER

Archie T. Brown, Biloxi, Miss.

Application March 9, 1950, Serial No. 148,600

2 Claims. (Cl. 222—173)

1

This invention relates to a condiment holder, and more particularly to a salt shaker.

The object of the invention is to provide a salt holder or shaker which is so constructed that practically no moisture can enter the interior of the shaker.

Another object of the invention is to provide a condiment holder that includes a plurality of discharge passageways which are sealed when the holder is placed on a table or other support surface.

Another object of the invention is to provide a condiment holder which is extremely simple and inexpensive to manufacture.

Other objects and advantages will be apparent during the course of the following description.

In the accompanying drawings, forming a part of this application and wherein like numerals are used to designate like parts throughout the same:

Figure 1 is a front elevational view of the condiment holder, according to the present invention;

Figure 2 is a rear elevational view of the holder;

Figure 3 is a sectional view taken on the line 3—3 of Figure 1; and

Figure 4 is a bottom plan view of the condiment holder.

Referring in detail to the drawings, the condiment holder is fabricated of suitable material and comprises a body 10 provided with an open end. The body 10 is shaped to define an interiorly threaded socket 11 and the socket 11 terminates in an interior chamber 12 for holding condiments, such as salt therein.

A head 13 is provided with an exteriorly threaded neck 14, and the threaded neck 14 is arranged in threaded engagement with the threaded socket 11 so that the open end of the body 10 is normally closed. The head 13 is provided with a bore 15 which communicates with the chamber 12 for receiving salt from the latter. The head 13 is shaped to define a circular rim portion 16 and a portion of the head is cut away to define a flat surface 17. A pair of spaced parallel passageways 18 and 19 are arranged in the head 13 and the passageways 18 and 19 extend from the flat surface 17 of the bore 15, the passageways serving to discharge the salt there-through as later described in this application.

Carried by the head 13 is a plurality of counterweights 20 and 21 which normally serve to retain the holder in the position shown in Figure 3 so that the outer ends of the passageways 18

and 19 will be closed by the supporting surface 22, which may be a table or other flat object.

A pin 23 is slidably and frictionally held by the rear end of the body 10 and the pin 23 is adapted to engage a portion of the supporting surface 22 so that the position of the body 10 can be adjusted as desired.

An additional sealing means is provided in the condiment holder and this means comprises a ball 24 which may be made of any suitable material, the ball 24 being held loosely in the bore 15 by means of a pin 25 which is secured to the head 13.

In use, salt or other condiments may be placed 15 in the chamber 12 of the body 10 and the neck 14 of the head 13 is threaded into the socket 11. Then, the holder is normally positioned on a supporting surface such as a table 22 so that the flat surface 17 of the head 13 abuts or is contiguous

20 to the supporting table 22. Thus, the outer ends of the passageways 18 and 19 will be respectively sealed so that moisture cannot enter the interior of the salt shaker to mix with the salt therein. Further, an additional sealing means is provided

25 and this additional means comprises the ball 24 which normally closes the inner ends of the passageways 18 and 19. The counterweights 20 and 21 normally hold the shaker in a position such that the flat surface 17 of the head 13 is contiguous to the supporting surface 22. Further, the pin 23 may be moved as desired in the body

10 so that there will be a fluid-tight seal between the supporting surface 22 and the outer ends of the passageways 18 and 19 when the shaker is positioned on a supporting body.

To discharge condiments such as salt from the shaker, the user merely grasps the shaker in his hand and shakes or moves the device back and forth. This will cause the ball 24 to move back and forth and the condiments will be permitted to discharge through the passageways 18 and 19, the ball 24 serving to effectively break the condiment up into small particles so that clogging of the device will be prevented.

45 While I have shown a certain embodiment of my invention, this is by way of illustration only, and I consider as my own as such modifications in construction as fairly fall within the scope of the appended claims.

I claim:

1. A condiment shaker comprising a body provided with a threaded socket, said socket terminating in a chamber for holding condiments, a pin slidably connected to the rear end of said body and adapted to engage a horizontal sup-

porting surface, a head provided with an exteriorly threaded neck arranged in engagement with said socket, there being a bore arranged in said head for receiving condiments from said chamber, a portion of the exterior of said head being shaped arcuately, another exterior portion of said head being shaped to define a flat surface, said head being provided with a pair of spaced passageways extending from said bore to said flat surface for the discharge therethrough of condiment, a plurality of counterweights for normally holding said flat surface in a position contiguous to the supporting surface, and a ball arranged in said bore and adapted to selectively seal and unseal the inner ends of said passageways.

2. A condiment shaker comprising a body provided with a socket, said socket terminating in a chamber for holding condiments, a pin slidably connected to the rear end of said body and adapted to engage a supporting surface, a head provided with a neck arranged in engagement with said socket, there being a bore arranged in said head for receiving condiments from said chamber, a portion of the exterior of said head being shaped

5 arcuately, another exterior portion of said head being shaped to define a flat surface, said head being provided with a plurality of spaced passageways extending from said bore to said flat surface for discharge therethrough of condiments, a plurality of counterweights normally holding said flat surface in a position contiguous to the supporting surface, and a ball arranged in said bore and adapted to selectively seal and unseal the inner ends of said passageways.
